UNITED STATES PATENT OFFICE

HERMAN C. PRIEBE, OF BLUE ISLAND, ILLINOIS

DRAFT GEAR

Application filed January 21, 1929. Serial No. 333,834.

My invention relates to draft gears for coupling cars into trains. One feature of the invention relates to those draft gears in which springs are located upon the outer sides of the center or draft sills and are coupled with draft gear elements between such sills to cooperate therewith in resisting draft strains. Hitherto it has been the practice to provide longitudinal extensions upon the followers that are between the sills and to pass keys through these extensions to establish assembly between these followers and the springs upon the exteriors of the sills, it being impracticable to pass such keys through the motion resisting portions of the gears that are between the sills, particularly where such motion resisting portions are in the form of springs having enclosing barrels that constitute follower 20 portions.

Where the followers are enlarged into spring barrels I provide lateral enlargements on the barrels and pass the keys snugly through slots that are formed in these 25 lateral barrel enlargements. As it is necessary for the outermost springs to be located upon the sides of the center or draft sills rather than above and below the same the lateral enlargements upon the barrels 30 are provided at the tops and bottoms of such barrels. In the preferred embodiment of my present invention the inner follower of a draft gear, alone, has been thus constructed to surround a central draft portion disposed along the line of draft and to receive the keys above and below this spring. These keys are extended to the outer sides of the center or draft sills and are assembled with supplemental followers upon the 35 outer sides of the sills that are pressed upon by and press upon the contiguous ends of the outer springs. The other follower receives but a single key which is passed therethrough at the axis of the gear and 40 which is assembled with other supplemental followers upon the exteriors of the sills that engage the other ends of the exterior springs. Viewed sidewise of the gear the keys are in triangular arrangement, the two 45 keys first referred to being at the base of the

triangle and equidistant from the axis of the gear that passes therebetween. The third key, which is at the apex of the triangle passes through the axis of the gear. The first two keys prevent the outermost 55 springs from buckling vertically. The third key prevents the outermost springs from buckling laterally. The three keys together thus prevent buckling of the outermost springs in any direction. While these 60 advantages are gained in a gear that is inclusive of two keys between which the central and inner portion of the gear passes other construction may be employed to secure these advantages without departing 65 from the invention.

In accordance with another characteristic of the invention I provide stop lugs upon the exteriors of the sills which lugs have wing extensions that embrace the key 70 which passes through the axis of the gear and margin the slots in the sills through which this key passes to restrengthen the sills in compensation for the weakness due to the removal of metal therefrom to form 75 the key receiving slots therethrough. In order that the springs upon the outer sides of the sills may be approached as closely to the sills as possible the aforesaid abutment wings are spread apart at their terminations 80 to receive the outer ends of the springs and their seats therebetween.

I will explain my invention more fully in connection with the accompanying drawings in which Fig. 1 is a plan view partially 85 in section illustrating a draft gear constructed in accordance with the preferred embodiment of the invention; Fig. 2 is a side elevation of the gear shown in Fig. 1 with parts broken away; and Figs. 3, 4, 5 90 and 6 are views taken respectively on lines 3—3, 4—4, 5—5 and 6—6 of Fig. 1.

The center sills 1 and 2 of the car desirably also constitute the draft sills of the gear. The coupler yoke 3 is disposed between the sills. This coupler yoke is of U form with its sides in the same horizontal plane and respectively closely approached to the center sills. The base of the coupler yoke is innermost. The outer end portions 100

of the coupler are formed with elongated slots 4. The key 5 snugly passes through a slot formed through the inner end of the coupler stem 6. The slots 4 are longer than the width of the key to permit inward movement of the key with respect to the coupler during compression, the key engaging and pulling upon the coupler yoke when the coupler stem is pulled upon. The center sills are provided with slots 7 which are of sufficient length to permit the full range of movement of the key 5. The outer follower 8 and the inner follower 9 are the main followers and are provided between the center or draft sills. The outer follower 8 is formed with a pin projection 10 which is received within the inner end of the coupler stem 6.

The motion resisting mechanism illustrated is inclusive of friction producing elements and spring means operating upon same. The friction producing means illustrated is inclusive of friction blocks 11, 11' and 11², other friction blocks 12, 12' alternating with the first. The friction blocks 11, 11² have abutting engagement with the follower 8, these friction blocks also having wedging engagement with this follower. The friction blocks 12 and 12' are of T form, the projecting ends of the T heads being caught by the extension 13 of the follower 9. The springs 16 are interposed between the friction blocks and the follower 9, these springs being surrounded by the follower extension 13 which is in the form of a spring barrel. These springs and said friction blocks cooperate to yieldingly oppose relative movement of the followers longitudinally of the gear in response to draft strains.

Supplemental springs 17 and 18 are provided upon the exteriors of the sills, these springs pressing upon and being pressed upon by the spring seats 19 and 20 which constitute supplemental followers. The supplemental followers are brought into assembly with the main followers by means of the keys 22, 23 and 24. The key 22 passes snugly through the follower 8 laterally of the gear, this key being cut by the axis of the gear. The keys 23 and 24 snugly pass through lateral enlargements provided at the top and bottom of the spring barrel 13. These latter keys are thus abreast of the motion resisting means 16 of the gear. The assembly of these keys 23 and 24 with the associated supplemental followers is established by means of the yokes 25 which are preferably in the form of vertical rods that are passed downwardly through the keys. These vertical rods are formed with holes therethrough at the mid-portions thereof through which the sides of the U bolts 26 are received. These U bolts 26 embrace the horizontal webs 27 upon the

corresponding followers whereby the U bolts and yokes are held from vertical displacement.

The keys viewed from the side of the gear define a triangle whose corners are determined by the three keys. Said keys, by reason of their length and relation, define a triangular prism and consequently cooperate to prevent buckling of the springs 16.

The key 22 is limited in its motion by means of stop lugs 28 that are provided upon the exteriors of the sills, these lugs having wing extensions 29 that embrace the key 21 substantially throughout the width of this key and margin the slots 30 in the sills through which the key 29 passes to compensate for the weakness in these slots. The members 28 and 29 are desirably integrally formed with castings 31 which have slots therethrough in register with the slots 30. These slots in said castings are also margined by the wings 29 to strengthen the castings in compensation for the loss of the material in the slots through the castings.

Structural characteristics not herein claimed, particularly the structural element providing the seats 19 and 20 form the subject matter of my copending application No. 333,833 filed of even date herewith.

Changes may be made without departing from the invention.

Having thus described my invention, I claim:

1. A draft gear including inner and outer followers; main motion resisting means interposed between and cooperating with said followers; draft sills between which the aforesaid elements are disposed; supplemental motion resisting means upon the exterior of the space between said sills and extending along the sills laterally thereof; a single member substantially at the level of the axis of the gear which effects assembly between one of said followers and the aforesaid supplemental motion resisting means; and members connected with top and bottom portions of the other follower and effecting assembly of this follower with said supplemental motion resisting means.

2. The structure of claim 1 wherein the main motion resisting means is between the two members that are connected with one follower.

3. The structure of claim 1 wherein the members that are connected with the followers are in the form of keys passing through the followers.

4. The structure of claim 1 wherein the members that are connected with the followers are in the form of keys and the main motion resisting means is included between the two keys that are connected with one follower.

5. The structure of claim 1 wherein the

members that are connected with the followers are in the form of keys and the main motion resisting means is in the form of a spring that is between the keys that are connected with one follower.

5 6. A draft gear including a follower carrying a member for limiting its motion; draft sills between which this follower is disposed and slotted to permit the passage of said member therethrough; supplemental motion resisting means upon the exterior of the space between the draft sills and inclusive of a spring; and a stop lug carried by a draft sill and formed with wings which 10 embrace the stop member upon the follower having this member and which wings margin the draft sill slot, these wings being flared to receive the spring of the supplemental motion resisting means and permit 15 this spring to lie close to the draft lug and this sill carrying it.

20 7. The structure of claim 6 in which the member upon the follower is in the form of a key which is snugly passed through the follower.

25 In witness whereof I hereunto subscribe my name.

HERMAN C. PRIEBE.
